APPARATUS FOR TREATING METAL SHEETS

Edward I. Huff, Reiffton, Pa., assignor to Huff
Equipment Company, Pittsburgh, Pa., a cor-
poration of Pennsylvania

Application July 27, 1936, Serial No. 92,725

9 Claims. (Cl. 214—21)

This invention is directed to apparatus for treating metal sheets, more particularly, to apparatus for the normalizing and annealing of metal sheets, in particular, steel sheets.

5 It has hitherto been the custom, in the continuous annealing or normalizing of steel sheets, to pass the sheets continuously through a furnace in a substantially horizontal position. This practice has many disadvantages, among which 10 may be mentioned the necessity for the use of "dummy" sheets, the necessity for providing water-cooled shafts for the rollers used, and the marking of the surface of the metal sheets being treated. It has been proposed, to avoid certain 15 of the difficulties encountered in passing steel sheets through a furnace in a horizontal position, to pass the steel sheets through a furnace while the sheets are in a vertical position. However, while some of the disadvantages of horizontal 20 treatment are avoided by such a procedure, serious difficulties in the satisfactory treatment of the steel sheets still remain. Thus, for example, the steel sheets are marked by the clamps used to support them as they pass through the furnace. 25 Moreover, the furnace construction necessary for the practice of this type of annealing, namely, a tunnel open at both ends, inevitably causes air currents which result in uneven heating of the steel sheets being annealed. Consequently, the sheets are twisted and warped to 30 some extent during the annealing process, and it has not been possible to produce a flat sheet uniformly annealed.

In accordance with my invention there is provided apparatus for the continuous annealing of, for example, sheet steel in which a uniform temperature is maintained throughout the furnace, and the steel sheet is supported in the furnace in a vertical position without the use of clamps or 35 any other device that would mark the surface of the annealed sheet. As a consequence, it is possible to obtain an annealed sheet that is unwarped, is uniformly annealed throughout, and is free from surface markings. Moreover, by the 40 provision of automatic control means it is possible to insure an absolute uniformity in the annealing treatment given each sheet of steel, while nevertheless retaining the utmost flexibility in the temperature and time factors of the annealing process.

In accordance with my invention, the sheets of steel or other metal to be normalized or annealed are fed successively in position beneath the annealing furnace. Each sheet in succession 45 is then automatically raised up into position in

the annealing furnace where it remains suspended vertically in the furnace until the desired heat treatment has been effected. The sheet is then lowered out of the furnace and automatically conveyed away from the furnace to a point 5 of discharge or to pickling, scrubbing vats, or the like.

The apparatus which is preferably utilized in accordance with my invention comprises a substantially completely enclosed annealing furnace 10 adapted to hold a single sheet of steel or other metal to be treated suspended vertically therein and provided with, as the sole opening, a relatively narrow slot in the bottom of the furnace through which the sheets of steel may enter and leave the furnace; a conveyor adapted to bring the sheets of steel successively into position beneath the furnace; hoisting means partially contained in the furnace for raising the steel sheets 15 from the conveyor into the furnace and lowering them again after the heat treatment is over onto the conveyor; and means for loading the steel sheets onto the conveyor and removing them from the conveyor.

The preferred embodiment of my invention 25 is shown in the accompanying drawings in which Fig. 1 is a front elevation, partly in section, of the apparatus in accordance with my invention, including the furnace conveyor and loading and unloading means.

Fig. 2 is an end view showing the discharge end of the apparatus shown in Fig. 1.

Fig. 3 is a vertical sectional view through the apparatus shown in Fig. 1, looking toward the 30 charging end of the apparatus.

Fig. 4 is a detail view showing the upper end of a sheet of steel or other metal prepared for treatment in the apparatus shown in Fig. 1.

Fig. 5 is a detail view of the carrier bar utilized for supporting the sheets of steel during 35 treatment.

Fig. 6 is a fragmentary, plan view of the sequence controller used in accordance with my invention for controlling the passage of the steel 40 sheets through the apparatus.

Fig. 7 is a plan view showing the time control device used for determining the interval of time during which the sheet steel remains in the furnace.

Fig. 8 is a diagrammatic wiring diagram showing the arrangement of interlocking controls used to secure proper sequence of operations and to prevent improper sequence of operations.

And Fig. 9 is a diagrammatic sketch showing 50 55

the operation of the sequence control illustrated in Fig. 6.

As is best shown in Fig. 1, the apparatus in accordance with my invention comprises a furnace, indicated generally by the reference character 1; a conveyor, indicated generally by the reference character 3, adapted to bring sheets of steel successively into position beneath the furnace; a hoisting mechanism, indicated generally 10 by the reference character 5, for raising the sheets of steel into the furnace and lowering them again onto the conveyor 3; a loading mechanism, indicated generally by the reference character 7, for feeding sheets of steel onto the conveyor 15 3; and an unloading mechanism, indicated generally by the reference character 9, for removing treated sheets of steel from the conveyor 3 and discharging them from the apparatus.

The furnace 1 is enclosed in a welded steel shell 20 11, which is supported in conventional manner from the buck-stays 13, the bottom tie members 15 and the top tie members 17. Inside the steel shell 11 is provided the usual heat insulating material 19 and refractory material 21. A plurality 25 of electric heating units 23 fixed on the interior wall of the heating chamber proper 25 provide the necessary heat. It will be noted that heating chamber 25 is substantially entirely enclosed, the only opening therefrom being the relatively narrow slit 27 at the bottom of the furnace.

The conveyor 3 is formed of a pair of endless chain members 31 passing around sprockets 33 and 35, respectively, and supported in the reaches between the sprockets by beams 35 and angle 30 plates 37 fixed to the upright supports 39. Sprockets 33 are fixed on a shaft 41 journaled in the T-shaped supporting members 43, while sprockets 35 are fixed on a similar shaft 45 journaled in the supporting members 47. Likewise 40 fixed on the shaft 45, is a ratchet wheel 49, which is engaged by a lever 51, acting as a pawl. Lever 51 is held against the ratchet wheel 49 by a spring 53 attached to the support 47, and is pivoted at its opposite end to the crank disc 55, which is 45 driven through a reduction gearing 57 by the electric motor 59. Fixed on the same shaft as the crank disc 55 is a cam 61 adapted to actuate in its rotation control switch C, carried on the support 47, of the interlocking control circuit.

The hoisting mechanism 5 comprises a pair of 50 drums or sprockets 71 mounted on a shaft 73 and enclosed in housings 75. The shaft 73 extends beyond the housing 75, across the top of the furnace, and is driven through gears 77, 79 by the 55 electric motor 81 supported on the top tie members 17 of the furnace. A pair of chains or cables 83 are secured to, and adapted to be wound on, the drums 71 and pass through openings 85 in the roof of the heating chamber 25. Positioned 60 within the heating chamber 25 and affixed to the lower ends of the chains or cables 83 is a carrier member 87 having inturned, concave flange elements 89 adapted to receive and hold the sheet metal carrier bar 91 shown in Fig. 5, which will be 65 hereinafter described.

Secured to one of the chains or cables 83 are 70 a pair of sleeve members 93 carrying a projection adapted to actuate the interlocking control switch E of the interlocking control circuit. Sleeves 93 are capable of being adjusted along the chain or cable 83 so that one of them will trip or actuate the switch arm 95 of switch E downwardly when the carrier 87 is in its lowermost position with the carrier bar 91 resting on the conveyor 3, while the other sleeve 93 will trip the

switch arm 95 upwardly when the carrier 87 is in its uppermost position adjacent the roof of the heating chamber 25.

The loading mechanism 7 and the unloading mechanism 9 are similar in construction and comprise cars 101 adapted to travel along the rails 103 positioned along the top of the furnace 1. Each car 101 carries an electric motor 105 and a drum 107 driven thereby. A pair of cables 109 are secured to and adapted to be wound on each 10 of the drums 107. These cables pass from the drums 107 over pulleys 111 and are fastened at their lower ends to the carrier 113. This carrier runs on rollers 115 within the track formed by channel members 117. Channel members 117 are 15 supported at their upper ends from the cars 101 and are free at their lower ends. The carrier 113 is provided with a pair of inturned concave flanges 119, similar to those of the carrier 87, and adapted, like those of the carrier 87, to receive 20 and support the carrier bars 91.

On one of the channel members 117 of the loading mechanism 7 there is provided a pair of interlocking control switches A and A'. These switches are adapted to be tripped or actuated by 25 the rollers 115 of the carrier 113. Switch A, positioned at the upper end of the channel member 117, is adapted to be actuated by the carrier 113 when it is in its uppermost position, while switch A', positioned at the lower end of channel mem- 30 ber 117, is adapted to be actuated when the carrier 113 is in its lowermost position. A similar pair of interlocking switches B and B' are provided on one of the channel members 117 of the un- 35 loading mechanism 9.

Each of the cars 101 is pivotally connected to a pair of links 121, which in turn are pivotally connected, at their other ends, to a pair of crank discs 123. The crank discs 123 are fixed on a shaft 125, which is journaled in the frame member 127 sup- 40 ported on the top tie members 17 of the furnace 1. Shaft 125 is driven through gears 129, 131 by electric motor 133. An arm or cam 135 is also fixed on the shaft 125 and is adapted to actuate, at every half revolution of the shaft 125, interlock control switch D.

A pair of links 141 are pivotally connected to the lower ends of the channel members 117 of the unloading mechanism 9, and these links 141 are 50 fixed at their other ends to stud shafts 143 journaled in the fixed frame member 47. Likewise fixed on the stud shafts 143 are gears 145 meshing with pinions 147 fixed on a second pair of stud shafts journaled in the fixed frame member 47. Fixed to these second stud shafts are a 55 pair of fingers 149 adapted, when raised in position, to receive and hold a carrier bar 91.

Positioned immediately beneath the fingers 149 and supported at its upper end by the fixed frame member 47 is a rollway 151 provided with a guide 60 plate 153 and rollers 155.

The sequence control mechanism shown in Fig. 6 comprises an electric motor 161 which drives, through reduction gearing 163, a drum 165. The drum 165 carries on its surface a plurality of contact members or strips 167 extending for various distances about the periphery of the drum, each of which is adapted to engage, on rotation of the drum, one of a plurality of fixed contacts 169. The closing of the various contacts 167, 169 closes 70 or opens switches in the various circuits to the motors 59, 81, 107 and 133, as shown diagrammatically in Fig. 9. In Fig. 9 each of the respective circuits shown is closed during rotation of the drum 165 over that portion of one revolution 75

of the drum represented by the heavy black lines.

In series with the switches closed or opened by the operation of the sequence control mechanism, as set out above, are the several switches shown 5 diagrammatically in Fig. 8, which switches are actuated, as shown in the figure, by the several interlocking control switches A, B, C, D, and E. It is accordingly apparent that before any particular motor or other actuating mechanism can 10 be energized, it is necessary that both the sequence control mechanism in its operation shall have closed the switches for that circuit and that the switches controlled by the interlock control mechanism shall likewise be closed.

15 The timing device shown in Fig. 7 comprises a motor 171 which drives through reduction gearing 173 the shaft 175, slidable along the shaft 175, but keyed thereto, is a friction wheel 177, which is in frictional engagement with the 20 face of plate 179 secured to one end of shaft 181. Disc 183 is mounted on shaft 181 and carries on its outer surface a contact member 185, which is adapted to engage, during a portion 25 of the rotation of disc 183, fixed contact 187. Contacts 185, 187 are positioned in the circuit for the sequence control mechanism motor 161, and this motor consequently is energized only 30 when these contacts are closed.

The friction wheel 177 is movable along the 35 shaft 175 and may be maintained in any desired position thereon by means of the guide member 189 which is threaded on the screw shaft 191. A pointer 193, attached to guide 189, indicates 40 on scale 195 the position of friction wheel 177 along the shaft 175. Screw shaft 191 may be 45 rotated by means of the knurled knob 197 affixed thereto.

In the treatment of metal sheets, for example, 50 steel sheets, in accordance with my invention, the sheets are first sheared approximately $1\frac{3}{4}$ " longer than the final length, and at the same time a plurality of holes evenly spaced along the end of the sheet and of elongated form to allow for expansion are punched in this edge portion. 55 Such a sheet is shown in Fig. 4, and is designated by the reference character 201, the holes being indicated by the reference character 203. After the sheets have been treated in accordance with my invention, the sheets are sheared along the line 205, and the extra length having the holes punched in it is thus removed.

The steel sheets 201 are carried through the apparatus supported on carrier bar 91 (Fig. 5). The body portion of this carrier bar 91 is a 60 channel section made of suitable material to withstand the temperatures to which it is subjected, and designed to absorb the least amount of heat possible. The web of the channel section will desirably be cored, cut or punched out, as shown at 209, in order to reduce the weight 65 thereof. Hooks 207 are attached to the channel section, at properly spaced intervals to correspond with the holes 203 in the sheet steel, either by welding or by being clamped by nuts 70 threaded on the shanks of the hooks.

In order to visualize the operation of the apparatus in accordance with this invention, let us assume that a sheet of steel 201 is being heated in the furnace chamber 25 and that the 75 various elements are in the position shown in Fig. 1. It will be noted that there are a plurality of steel sheets 201 hanging in the pit 26 below the furnace, supported from the carriers 80 resting on the conveyor 3. Those sheets of 85 steel to the left of the furnace opening 27 have

as yet not been heat treated, while those to the right of the furnace opening have been heat treated in the furnace. It will be seen that the heat given off by the treated sheets in the pit 26 is to a large extent absorbed by the untreated 5 sheets which consequently receive a certain degree of preheating before being placed in the furnace chamber 25. The carrier 113 of the loading mechanism 7 is in its lowermost position with a bar carrier 91 resting in the flanges 10 119. The hooks 207 of this particular bar carrier 91 are firmly supported against the fixed bar 211 secured in the T-shaped supporting members 43. A fresh sheet of steel 201 is then 15 manually placed on the hooks 207 of this bar 20 carrier 91.

In the meantime the motor 171 of the timing control mechanism has been running, and consequently the shaft 181 and the disc 183 have 20 been rotating at a speed determined by the position of the friction wheel 177 along the shaft 175. When the steel sheet 201 within the heating chamber 25 has been in this chamber for the predetermined period of time for which the timing control mechanism has been set by adjustment 25 of the friction wheel 177 by means of the knob 197, the contacts 185 and 187 are closed through the rotation of the disc 183. When these contacts are closed, the motor 161 of the sequence control mechanism is started and drum 30 165 begins to rotate. This point is indicated in Fig. 9 by the first arrow at the top of the figure. As the drum 165 rotates, the circuit to the timer motor 171 is broken, and the action of the timing device stops. At the same time 35 the circuit to the chamber hoist motor 81 is closed and, the reversing switch and power switch controlling this motor, as shown in Fig. 8, being in the proper position by reason of the action of the interlock control contacts in the 40 completion of the last cycle of operation, the motor 81 is energized to rotate the drums 71 and lower the carrier 87 bearing the sheet 201 undergoing treatment.

This lowering action continues until the carrier bar 91 is deposited on the chains 31 of the conveyor 3 and until the carrier 87 has descended an additional distance sufficient to disengage the flanges 89 thereof from the bar carrier 91. At 45 this moment one of the sleeves 93 on the chains 50 or cables 83 actuates switch arm 95 of the interlock contact switch E downwardly. As shown in Fig. 8, this action closes control circuits which (1) open the power switch and de-energize the motor 81, thus stopping the lowering of the carrier 87, (2) throw the reversing switch governing the operation of motor 81 from down to up 55 position, and (3) close the power switch controlling the operation of motor 59.

The power switch controlling the operation 60 of motor 59 being closed, the further rotation of drum 165 of the sequence control mechanism closes the circuit leading to the conveyor motor 59 and energizes this motor. Crank disc 55 is thereby given one complete revolution, which 65 motion is transferred to the ratchet wheel 49 by the action of arm 51, and advances this ratchet wheel one notch, thereby moving the conveyor chains 31 a sufficient distance to bring the bar carrier 91, on which is suspended the 70 sheet of steel 201 next to be treated, directly above the flanges 89 of the lowered carrier 87. In the meantime, the cam 61 rotating with the crank disc 55 actuates the interlock control contact C. Actuation of this contact, as shown 75

in Fig. 8, results in closing the control circuits which (1) close the power switch in the circuit leading to motor 81, and (2) open the power switch in the circuit leading to motor 59, thus 5 stopping further rotation of the crank disc 55 and further movement of the conveyor 3.

The continued rotation of the drum 165 of the sequence control mechanism again closes the circuit leading to the chamber hoist motor 81, and 10 the power switch in this circuit having been closed through actuation of contact C, motor 81 is again energized, this time serving to raise the carrier 87, which brings with it the bar carrier 91 and the sheet 201 to be treated, into the furnace chamber 15 25. As the carrier 87 reaches its uppermost position adjacent the top of the furnace chamber 25, the second sleeve 93 on the cable or chain 82 actuates the interlock control switch E, this time in an upward direction. Such actuation of the 20 control switch E, as shown in Fig. 8, closes control circuits which (1) throw the power switch in the circuit to motor 81 off, thus stopping the motor and the upward movement of the carrier 87, and (2) throw the reversing switch governing the 25 operation of motor 81 from up to down position.

As this is done, continued rotation of the drum 165 of the sequence control mechanism closes the circuit starting timer motor 171 which sets in 30 operation the timing control mechanism that will serve to determine the period of time that this sheet 201 will remain in the furnace chamber 25. At the same time the sequence control mechanism 35 closes switches in the circuits to the two motors 105 which control the loading and unloading mechanisms 7 and 9. The power switches for these motors controlled by the interlock control mechanism being in closed position, and the reversing switch therefor being set in position for upward movement, these motors are energized to 40 draw the carriers 113 upwardly. This action raises the fresh sheet of steel that had been manually placed on the hooks 207 of the bar carrier 91 resting against the stop 211 up between the channel members 117 of the loading mechanism and at 45 the same time raises the treated steel sheet in the extreme right position on the conveyor 3 up between the channel members 117 of the unloading mechanism 9.

As the two carriers 113 reach their uppermost 50 position within the channel members 117, they actuate interlock control switches A and B, respectively. The actuation of control switch A, as shown in Fig. 8, throws the power switch in the circuit controlling the operation of the corresponding motor 105 into off position, thus stopping the upward movement of the corresponding carrier 113. Similarly the actuation of switch B 55 throws the power switch and the circuit controlling the operation of that motor 105 into off position. When both switches A and B have thus been actuated, the reversing switch in the circuit to motors 105 is thrown from up to down position, and the power switch in the circuit leading to motor 133 is thrown into closed position.

60 Continued rotation of the drum 165 of the sequence control mechanism closes the circuit leading to motor 133, and the power switch controlled by the interlock control mechanism in this circuit having already been closed by the action of control switches A and B, this motor 133 is energized. Crank discs 123 are thereby rotated until the operation of cam 135 actuates interlock control switch D, which de-energizes motor 133 and stops the 65 rotation of the crank discs 123 after they have completed a half revolution. Crank discs 123, in

70 completing a half revolution, move cars 101 along the rails 103 by means of the connecting links 121 to the position shown by the dotted lines in Fig. 8.

The operation of switch D, as shown in Fig. 8, in addition to throwing the power switch in the 75 circuit leading to motor 133 into off position, also throws the power switches leading to motors 105 and motor 81 into on, or closed, position.

Continued rotation of the drum 165 of the sequence control mechanism operates to energize 10 once more motors 105. This time, by reason of the actuation of the reverse switches through the interlock control mechanism, in a direction to lower the carriers 113. The bar carrier 91 and the steel sheet 201 carried by carrier 113 of the 15 loading mechanism 7 is thereby deposited at the extreme left end of conveyor 3, while the bar 91 and steel sheet 201 carried by the unloading mechanism 9 is deposited on the fingers 149, which have been raised into horizontal position by 20 the movement of channel members 117 into the position shown by the dotted lines in Fig. 1. As the respective carriers 113 reach their lowermost position, they actuate interlock control switches A' and B', which, as shown in Fig. 8, de-energize 25 the motors 105, throw the reversing switch governing the operation of these motors from down to up position, and throw the power switch of the circuit leading to motor 133 from off to on position.

Continued further rotation of the drum 165 30 then energizes motor 133 to cause the crank discs 123 to undergo a further half revolution with the resultant movement of cars 101 and the loading and unloading mechanism carried back into the position shown in the solid lines in Fig. 1. 35 The rotation of crank discs 123 is stopped after one-half revolution by actuation of interlock control switch D, as described above, and the consequent de-energization of motor 133.

The continued rotation of drum 165 then operates to open the circuit leading to motor 161, thus 40 stopping further operation of the sequence control mechanism. The timing control mechanism, however, continues to run until, after the sheet 201 has been in the heating chamber 125 for the 45 predetermined period of time, the sequence control motor is started thereby, and the entire sequence of operations just described is repeated.

As channel members 117 of the unloading mechanism 9 move back into the position shown 50 in the solid lines in Fig. 1, as just described, the fingers 149 are dropped from their horizontal position into the position shown in the solid lines in Fig. 1, and the bar carrier 91 and steel sheet 201 supported thereby are permitted to slide down the 55 railway 151.

It will be seen that in the operation just described in detail above that a sheet of steel is taken by the loading mechanism 7, raised, brought into position over the end of conveyor 60 3, and lowered into position on the conveyor, while at the same time, at the right hand side of the conveyor a treated sheet has been raised from the conveyor, moved over above the fingers 149, and then lowered and discharged from the 65 apparatus along the railway 151. Meanwhile, the chamber hoist mechanism 15 has picked up a bar carrier 91 and steel sheet 201 from the conveyor 3, raised them through the opening 27 into the furnace chamber 25, and maintained 70 them there for such period of time as is necessary for the desired heat treatment. The chamber hoist mechanism 5 has then lowered the sheet of steel back onto the conveyor 3, which has then been moved forward so as to bring the 75

next sheet of steel under the opening 27. Ultimately the sheet of steel placed by the loading mechanism at the extreme left end of conveyor 3 will be brought beneath the furnace, raised 5 up and heat treated in the furnace, lowered back on the conveyor, moved to the extreme right hand position on conveyor 3, and discharged from the apparatus by unloading mechanism 9.

It will be appreciated that, if desired, the unloading mechanism 9 may place the heat treated steel sheets directly on another chain conveyor similar to the conveyor 3, which will carry them to or through any suitable after treatment, such as pickling, scrubbing, etc. It will also be appreciated that any desired pre-treatment may be given the steel sheets, and that the mechanism 7 may be designed to pick up from a chain conveyor the sheets of steel that have undergone such pre-treatment and place them, as described, 20 on the conveyor 3.

It will further be appreciated that, while an electrically heated furnace 1 has been described, that such furnace may, within the scope of this invention, be heated in any conventional manner, as by gas and the like.

Many other modifications of my invention will be apparent to those skilled in the art, and it is accordingly to be understood that my invention is not to be treated as limited to the particular 25 details of construction and operation set out above.

What I claim and desire to protect by Letters Patent is:

1. Apparatus for the treatment of metal sheets including in combination a furnace having a heating chamber open only at the bottom thereof and adapted to receive at least a single sheet of metal positioned vertically, a pit positioned beneath said furnace, a conveyor traveling beneath said furnace and above said pit, means for moving said conveyor intermittently, a plurality of carrier bars adapted to rest transversely on said conveyor and provided with means attachable to an edge of a metal sheet to be treated, 35 whereby a plurality of metal sheets may hang vertically in said pit suspended from said carrier bars resting on said conveyor, a carrier normally positioned in said furnace chamber and adapted to engage any of said carrier bars, means for lowering said carrier from said furnace chamber into proximity to said conveyor and for raising it into said chamber again, whereby a carrier bar and attached metal sheet may be raised from said conveyor into the furnace 40 chamber and replaced on said conveyor again, hoisting means adapted to place a carrier bar and attached metal sheet on said conveyor adjacent one end thereof, and hoisting means adapted to remove a carrier bar and attached metal sheet 45 from the conveyor at the opposite end thereof.

2. Apparatus for the treatment of metal sheets including in combination a furnace having a heating chamber open only at the bottom thereof and adapted to receive at least a single sheet of metal positioned vertically, a pit positioned beneath said furnace, a conveyor traveling beneath said furnace and above said pit, means for moving said conveyor intermittently, a plurality of carrier bars adapted to rest transversely on said 50 conveyor and provided with means attachable to an edge of a metal sheet to be treated, whereby a plurality of metal sheets may hang vertically in said pit suspended from said carrier bars resting on said conveyor, a carrier normally positioned in said furnace chamber and adapted to engage any of said carrier bars, means for lowering said carrier from said furnace chamber into proximity to said conveyor and for raising it into said chamber again, whereby a carrier bar and attached metal sheet may be raised from said conveyor into the furnace chamber and replaced on said conveyor again, means adapted to place a carrier bar and attached metal sheet on said conveyor adjacent one end thereof, and means adapted to remove a carrier bar and attached metal sheet from the conveyor at the opposite end thereof.

engage any of said carrier bars, means for lowering said carrier from said furnace chamber into proximity to said conveyor and for raising it into said chamber again, whereby a carrier bar and attached metal sheet may be raised from said conveyor into the furnace chamber and replaced on said conveyor again, hoisting means adapted to place a carrier bar and attached metal sheet on said conveyor adjacent one end thereof, and hoisting means adapted to remove a carrier bar and attached metal sheet from the conveyor at the opposite end thereof, at least one of said two last named hoisting means comprising a track positioned above said furnace and extending longitudinally of said conveyor, a car adapted to run on said track, hoist mechanism mounted on said car, a pair of spaced guide members attached to said car and extending vertically beneath the car into proximity to said conveyor, a carrier adapted to engage any of said carrier bars connected to said hoist mechanism and adapted to run between said guide members, and means for moving said car along said track.

3. Apparatus as defined in claim 1 including in addition control means adapted to effect automatically in predetermined sequence and at predetermined intervals the operation of the mechanism described in said claim.

4. Apparatus as defined in claim 1 including in addition control means adapted to effect automatically in predetermined sequence and at predetermined intervals the operation of the mechanism described in said claim and independent interlock control means adapted to prevent positively the effecting of an operation designed in 35 normal sequence to succeed a preceding operation until such preceding operation shall have been completed.

5. Apparatus for the treatment of metal sheets including in combination a furnace having a heating chamber open only at the bottom thereof and adapted to receive at least a single sheet of metal positioned vertically, a conveyor traveling beneath said furnace, means for moving said conveyor intermittently, a plurality of carrier bars adapted to rest transversely on said conveyor and provided with means attachable to an edge of a metal sheet to be treated, whereby a plurality of metal sheets may hang vertically suspended from said carrier bars resting on said conveyor, a carrier normally positioned in said furnace chamber and adapted to engage any of said carrier bars, means for lowering said carrier from said furnace chamber into proximity to said conveyor and for raising it into said chamber again, whereby a carrier bar and attached metal sheet may be raised from said conveyor into the furnace chamber and replaced on said conveyor again, means adapted to place a carrier bar and attached metal sheet on said conveyor adjacent one end thereof, and means adapted to remove a carrier bar and attached metal sheet from the conveyor at the opposite end thereof.

6. Apparatus as defined in claim 5 including 65 in addition control means adapted to effect automatically in predetermined sequence and at predetermined intervals the operation of the mechanism described in said claim.

7. Apparatus as defined in claim 5 including 70 in addition control means adapted to effect automatically in predetermined sequence and at predetermined intervals the operation of the mechanism described in said claim and independent interlock control means adapted to prevent posi-

tively the effecting of an operation designed in normal sequence to succeed a preceding operation until such preceding operation shall have been completed.

- 5 8. Apparatus for the treatment of metal sheets including in combination a furnace having a heating chamber open only at the bottom thereof and adapted to receive at least a single sheet of metal positioned vertically, a conveyor traveling beneath said furnace, a plurality of carrier bars adapted to rest on said conveyor and provided with means attachable to an edge of a metal sheet to be treated, whereby a plurality of metal sheets may hang vertically suspended from said carrier bars resting on said conveyor, a carrier normally positioned in said furnace chamber and adapted to engage any of said carrier bars, means for lowering said carrier from said furnace chamber into proximity to said conveyor and for raising it into said chamber again, whereby a carrier bar and attached metal sheet may be raised from said conveyor into the furnace chamber and replaced on said conveyor again, means adapted to place a carrier bar and attached metal sheet on said conveyor adjacent one end thereof, and means adapted to remove a

carrier bar and attached metal sheet from the conveyor at the opposite end thereof.

9. Apparatus for the treatment of metal sheets including, in combination, a furnace having a heating chamber provided with a narrow opening at the bottom adapted to permit the passage of a single sheet of metal positioned vertically, a conveyor traveling beneath said furnace, a plurality of carrier bars adapted to rest on said conveyor, each provided with means attachable to an edge of a metal sheet to be heated and adapted to hold only a single sheet, whereby a plurality of metal sheets may hang vertically suspended from said carrier bars resting on said conveyor, means adapted to engage any one of said carrier bars to raise it with its attached metal sheet from said conveyor through said narrow opening into said furnace chamber and to replace it in similar manner on said conveyor again, means adapted to place a carrier bar and attached metal sheet on said conveyor adjacent one end thereof, and means adapted to remove the carrier bar and attached metal sheet from the conveyor at the opposite end thereof.
